**D-ERYTHRO-D-GALACTO-OCTOPYRANOSE
DERIVATIVES**

Brian Bannister, Kalamazoo, and Herman Hoeksema, Cooper Township, Kalamazoo County, Mich., assignors to The Upjohn Company, Kalamazoo, Mich., a corporation of Delaware

No Drawing, Filed June 15, 1964, Ser. No. 375,334
14 Claims. (Cl. 260—210)

This invention relates to novel compositions of matter and is more particularly concerned with N-acyl-2-alkyl-3,4-O-isopropylidene-1-deoxylincosamine [6-acylamino-2-O-alkyl-1,6,8-trideoxy-3,4-O-isopropylidene-D-erythro-D-galacto-octopyranose] (VIII); N-acyl-2,7-di-O-alkyl-3,4-O-isopropylidene-1-deoxylincosamine [6-acylamino-2,7-di-O-alkyl-1,6,8-isopropylidene-D-erythro-D-galacto-octopyranose] (IX); novel processes for the production of

2

these compounds and for N-acetyl-7-O-alkyl-3,4-O-isopropylidene-1-deoxylincosamine [6-acylamino-7-O-alkyl-1,6,8-trideoxy-3,4-O-isopropylidene-D-erythro-D-galacto-octopyranose] (VII) and the intermediates in this process and analogues, particularly 7-O-alkyl-1-deoxylincosamine [6-amino-1,6,8-trideoxy-7-O-alkyl-D-erythro-D-galacto-octopyranose] (XIII); 2-O-alkyl-1-deoxylincosamine [6-amino-1,6,8-trideoxy-2-O-alkyl-D-erythro-D-galacto-octopyranose] (XIV); 2,7-di-O-alkyl-1-deoxylincosamine [6-amino-1,6,8-trideoxy-2,7-di-O-alkyl-D-erythro-D-galacto-octopyranose] (XV) and the like.

This application is a continuation-in-part of application S.N. 359,448, filed Apr. 13, 1964, now U.S. Patent 3,255,174.

The process of the present invention and the intermediate and final products therein can be illustratively represented in the following sequence of formulae:

wherein R_1 is selected from the group consisting of alkyl and aralkyl containing from 1 to 11 carbon atoms, inclusive, and wherein R_2 is an alkyl group having from 1 to 12 carbon atoms, inclusive.

Representative R_1 groups include: methyl, ethyl, propyl, butyl, pentyl, hexyl, heptyl, octyl, nonyl, decyl, undecyl, phenyl, benzyl, phenethyl, 3-phenylbutyl, 3-phenylpentyl, branched chain isomers such as isopropyl, isobutyl, isopentyl, t-butyl, neopentyl, and the like.

Representative R_2 groups include: methyl, ethyl, propyl, butyl, pentyl, hexyl, heptyl, octyl, nonyl, decyl, undecyl, dodecyl, and branched isomers thereof, and the like.

The process of the present invention comprises: treating a methyl N -acyl- α -thiolincosaminide (I) with dry acetone in the presence of an acid catalyst, for example sulfuric acid, to give a mixture of methyl N -acyl-3,4-O-isopropylidene- α -thiolincosaminide (III) and the oxazoline derivative thereof (II); hydrolyzing compound (II) in hot water to convert it to methyl N -acyl-3,4-O-isopropylidene- α -thiolincosaminide (III); methylation of compound (III) with an alkyl halide selected from the group consisting of alkyl chlorides, alkyl bromides and alkyl iodides in which the alkyl group has from 1 to 12 carbon atoms, inclusive, in the presence of a base and separating the three products thus obtained: methyl N -acyl-3,4-O-isopropylidene-7-O-alkyl- α -thiolincosaminide [methyl 6-acylamino-6,8-dideoxy-3,4-O-isopropylidene-7-O-alkyl-1-thio-D-erythro-alpha-D-galacto-octopyranoside] (IV); methyl N -acyl-3,4-O-isopropylidene-2-O-alkyl- α -thiolincosaminide [methyl 6-acylamino-6,8-dideoxy-3,4-O-isopropylidene-2-O-alkyl-1-thio-D-erythro-alpha-D-galacto-octopyranoside] (V); and methyl N -acyl-3,4-O-isopropylidene-2,7-di-O-alkyl- α -thiolincosaminide [methyl 6-acylamino-6,8-dideoxy-3,4-O-isopropylidene-2,7-di-O-alkyl-1-thio-D-erythro-alpha-D-galacto-octopyranoside] (VI); desulfurizing compounds IV, V and VI individually with nickel catalyst in a lower alkanol to obtain N -acyl-7-O-alkyl-3,4-O-isopropylidene-1-deoxylincosamine (VII); N -acyl-2-O-alkyl-3,4-O-isopropylidene-1-deoxylincosamine (VIII), and N -acyl-2,7-di-O-alkyl-3,4-O-isopropylidene-1-deoxylincosamine (IX).

Compounds IV, V and VI and compounds VII, VIII and IX can be treated with a dilute mineral acid, e.g. hydrochloric, sulfuric, and the like acids, to eliminate the isopropylidene moiety and with hydrazine to remove the acyl group attached to the amino nitrogen. In this manner the new compounds methyl-7-O-alkyl- α -thiolincosaminide (X), methyl 2-O-alkyl- α -thiolincosaminide (XI), methyl 2,7-O-alkyl- α -thiolincosaminide (XII); 7-O-alkyl-1-deoxylincosamine (XIII), 2-O-alkyl-1-lincosamine (XIV), and 2,7-di-O-alkyl-1-deoxylincosamine (XV) are obtained. Alternatively, compounds X, XI and XII can be desulfurized with a nickel catalyst, e.g. Raney nickel, to give the compounds of Formulae XIII, XIV and XV.

The novel compounds of Formulae VIII and X through XV, inclusive, are useful intermediates for the production of plastic materials. For example they can be reacted with isocyanates to form urethanes and ureas, and can be used to modify polyurethane resins. Thus, these compounds can be reacted with an excess of toluene diisocyanate to form a prepolymer which can then be reacted

with polyol ethers and polyol esters, commonly used to form polyurethanes; alternatively, these compounds can be mixed with polyol compounds and the mixture then reacted with toluene diisocyanate. The 2-O-, 7-O-, and 2,7-di-O-alkyl-1-deoxylincosamines and the methyl 2-O-, 7-O- and 2,7-di-O-alkyl-1-thiolincosaminides can also be reacted with ethylene oxide, propylene oxide, and like alkylene oxides to form polyoxoalkylene 2-O-, 7-O-, and 2,7-di-O-alkyl-1-deoxylincosamines and methyl 2-O-, 7-O-, and 2,7-di-O-alkyl-thiolincosaminides, which can be reacted with toluene diisocyanate to form a polyurethane. The compounds VII and VIII are particularly useful for producing rigid polyurethane foams. They also condense with formaldehyde, especially when the thiocyanic acid addition salt is employed, to form polymers according to U.S. Patents 2,425,320 and 2,606,155 which are useful as pickling inhibitors. The fluosilicic acid addition salts of compounds VII, VIII and X through XV are also useful as mothproofing agents in accordance with U.S. Patents 2,915,334 and 2,075,359.

The novel compounds IV, V and VI are not only new intermediates for the productions of the novel compounds VIII and IX and the known compound VII (U.S. application Ser. No. 359,448, filed Apr. 13, 1964, now U.S. Patent 3,255,174), but they can also be hydrogenated to the corresponding 6-alkylamino derivatives which upon reaction with thiocyanatoacetic acid yields insecticides useful, for example, in sprays against flies and mosquitoes.

In carrying out the process of the present invention, a methyl N-acyl- α -thiolincosaminide (I), in which the acyl group has from 2 to 12 carbon atoms, is suspended in dry acetone. An acid catalyst such as sulfuric acid, p-toluenesulfonic acid, o-toluenesulfonic acid, p-ethylbenzenesulfonic acid, or the like is added to the suspension, with sulfuric acid preferred. The acetone is generally used in large excess, such as a volume of 20 to 200 times the amount of the methyl N-acyl- α -thiolincosaminide. The acid catalyst is used in a quantity between 0.25 and 5% by weight with respect to the acetone. The reaction can be carried out between 10° and the reflux temperature of the solution, but is generally carried out at room temperature. The reaction time is between 15 minutes and 6 hours, depending on the temperature. After the reaction is terminated, the mixture is neutralized, inorganic salts precipitated by the neutralization are removed by filtration, and the filtrate is evaporated to give a mixture containing crystalline solids. This mixture is separated with water into a water-soluble and water-insoluble fraction; the water-soluble material is the methyl N-acyl-3,4-O-isopropylidene- α -thiolincosaminide (III); the insoluble fraction is the oxazoline derivative thereof (II).

The water-insoluble oxazoline derivative of methyl N-acyl-3,4-O-isopropylidene- α -thiolincosaminide can be converted to methyl N-acyl-3,4-O-isopropylidene- α -thiolincosaminide by heating with water. After this hydrolysis is complete, the product is obtained by evaporating the solution until crystallization occurs.

The alkylation of the methyl N-acyl-3,4-O-isopropylidene- α -thiolincosaminides is performed with an alkyl halide, preferably an alkyl chloride, bromide or iodide, in the presence of a strong base. As alkylating agents, methyl iodide, methyl bromide, ethyl iodide, ethyl bromide, and propyl, butyl, isobutyl, pentyl, hexyl, heptyl, octyl, nonyl, decyl, undecyl, dodecyl chlorides, bromides and iodides and any of the branched-chain alkyl chlorides, bromides or iodides having up to 12 carbon atoms can be used. As a base, alkoxides, such as sodium methoxide, potassium methoxide, potassium isopropoxide, potassium tert-butoxide, sodium tert-butoxide, sodamide and the like can be used. The alkylation can be performed at a temperature between 0° and 50° C. using inert solvents such as benzene, toluene, dioxane, tetrahydrofuran, and the like. After the reaction is terminated—usually between 1/2 hour and 3 hours—the reaction mixture is filtered to remove solids, such as sodium or potassium chloride, bro-

mide or iodide, and the filtrate is evaporation in vacuo to a syrupy residue. The three products therein, namely methyl N-acyl-7-O-alkyl-3,4-O-isopropylidene- α -thiolincosaminide (IV); methyl N-acyl-2-O-alkyl-3,4-O-isopropylidene- α -thiolincosaminide (V); and methyl N-acyl-2,7-di-O-alkyl-3,4-O-isopropylidene- α -thiolincosaminide (VI), are separated by conventional methods. The separation can be made by chromatography or, preferably, by counter current distribution as shown in the examples.

The desulfurization of compounds IV, V and VI is achieved by heating them under reflux in ethanol with loosely packed Raney nickel for a period of 2 to 24 hours. Thereafter, the catalyst is removed by filtration and the filtrate is evaporated to give a residue which can be purified by conventional means such as recrystallization from organic solvents. In this manner are obtained

N-acyl-7-O-alkyl-3,4-O-isopropylidene-1-deoxylincosamine (N-acyl-7-O-alkyl-3,4-O-isopropylidene-1,5-anhydrolincosaminol) (VII);
N-acyl-2-O-alkyl-3,4-O-isopropylidene-1-deoxylincosamine (N-acyl-2-O-alkyl-3,4-O-isopropylidene-1,5-anhydrolincosaminol) (VIII); and
N-acyl-2,7-di-O-alkyl-3,4-O-isopropylidene-1-deoxylincosamine (N-acyl-2,7-di-O-alkyl-3,4-O-isopropylidene-1,5-anhydrolincosaminol) (IX).

The methyl N-acyl-3,4-O-isopropylidene-7-O-, -2-O-, or -2,7-di-O-alkyl- α -thiolincosaminides are converted to methyl N-acyl-7-O-, 2-O-, or 2,7-di-O-alkyl- α -thiolincosaminide by hydrolysis with a dilute mineral acid, e.g. aqueous 0.1 to 0.5 N hydrochloric, hydrobromic, sulfuric acid or the like, with hydrochloric acid preferred. The reaction can be carried out between 10° and 50° C., preferably at room temperature, between about 20° and 30° C. At the termination of the reaction the product is isolated by conventional methods, e.g. neutralizing the solution with an anion exchange resin such as Amberlite IRA-400, filtering to remove the resin and evaporating the solution.

The thus-obtained methyl N-acyl-2-O-, 7-O- or 2,7-di-O-alkyl- α -thiolincosaminides are heated under reflux with hydrazine hydrate for a period of 4-48 hours, usually between 18 and 24 hours to give the corresponding methyl 7-O-alkyl- α -thiolincosaminide (X), methyl 2-O-alkyl- α -thiolincosaminide (XI), and methyl 2,7-di-O-alkyl- α -thiolincosaminide (XII). Compounds X, XI or XII in crude form are isolated from the reaction mixture by distilling excess hydrazine hydrate in vacuo. Purification of the crude material is carried out by conventional means, such as recrystallization from solvents, e.g. methanol, ethanol, ethyl acetate, Skellysolve B hexanes, mixtures thereof, and the like.

In the same manner, hydrolyzing and hydrazinolyzing N-acyl-7-O-, 2-O-, or 2,7-di-O-3,4-O-isopropylidene-1-deoxylincosamine as discussed above yield 7-O-alkyl-1-deoxylincosamine (XIII), 2-O-alkyl-1-deoxylincosamine (XIV) and 2,7-di-O-alkyl-1-deoxylincosamine (XV).

The following examples are illustrative of the process and products of the present invention, but are not to be construed as limiting.

EXAMPLE 1

Methyl N-acetyl-3,4-O-isopropylidene- α -thiolincosamine (III) and the oxazoline (II) derived therefrom

A. METHYL α -THIOLINCOOSAMINIDE

A solution of 4 g. of lincomycin (U.S. Patent 3,086,912) in 20 ml. of hydrazine hydrate (98-100%) was refluxed for 21 hours; excess hydrazine hydrate was then removed in vacuo under nitrogen at steam bath temperature. The residue, a pasty mass of crystals, was cooled, acetonitrile was added, and the mixture was stirred until the crystals were suspended. The crystals were collected on a filter and washed with acetonitrile and with ether. The yield of white, crystalline methyl α -

thiolincosaminide after drying in vacuo at room temperature was 2.1 g. (84%). Recrystallization was accomplished by dissolving the methyl α -thiolincosaminide in hot dimethylformamide and adding an equal volume of ethylene glycol dimethyl ether.

Methyl α -thiolincosaminide has a melting point of 225–228° C., an optical rotation of $[\alpha]_D^{25} + 276^\circ$ (c., 0.768, water), and a pKa' of 7.45.

Analysis.—Calcd. for $C_9H_{19}NO_5S$: C, 42.7; H, 7.56; N, 5.53; S, 12.66. Found: C, 42.6; H, 7.49; N, 5.75; S, 12.38.

B. METHYL N-ACETYL- α -THIOLINCOSAMINIDE

Five grams of methyl α -thiolincosaminide (about 0.02 mole) was suspended with stirring in 50 ml. of methanol and treated with 4.04 g. (about 0.04 mole) of acetic anhydride. The starting material dissolved almost completely, and thereafter the mixture became solid. After 18 hours at room temperature (about 25° C.), the solid was filtered, washed with methanol, and dried in a vacuum oven at 50° C. and 15 mm. pressure; yield, 4.58 g. (79%) of crystalline product melting at 242–245° C. This product was recrystallized from absolute methanol to give colorless needles of methyl N-acetyl- α -thiolincosaminide having a melting point of 243–245° C. and a rotation $[\alpha]_D^{25} + 265^\circ$ (c., 0.7374, water).

Analysis.—Calcd. for $C_{11}H_{21}NO_6S$: C, 44.72; H, 7.17; N, 4.74; S, 10.85. Found: C, 44.87; H, 7.10; N, 4.65; S, 10.99.

C. METHYL N-ACETYL-3,4-O-ISOPROPYLIDENE- α -THIOLINCOSAMINIDE AND THE OXAZOLINE DERIVED THEREFROM

Sixteen grams of methyl N-acetyl- α -thiolincosaminide was finely powdered and suspended in 1600 ml. of dry acetone with rapid magnetic stirring. To this suspension was added 16 ml. of concentrated sulfuric acid. The suspended solid began to dissolve and solution was complete within 30 to 60 minutes. After standing for 3 hours at room temperature (24–26° C.), the solution was cooled overnight in a refrigerator at about 5 to 10° C.

The pale yellow solution was neutralized by introducing, with stirring, a stream of dry ammonia gas. Ammonium sulfate precipitated and was removed by filtration and washed with acetone. The acetone washing was added to the colorless filtrate which was evaporated on a rotating evaporator at 30° C. and 15 mm. Hg pressure, to yield a mixture of syrup and crystalline solids. The syrup was dissolved by swirling the mixture with 50 ml. of water, and the crystalline solid was collected on a filter and washed with ice-cold water. Upon drying at 60° C. and 15 mm. Hg pressure, 7.12 g. of solids were obtained of melting point 189–192° C. Recrystallization from acetone-Skellysolve B hexanes gave colorless needles of the oxazoline derived from methyl N-acetyl-3,4-O-isopropylidene- α -thiolincosaminide; melting point, 191–192.5° C.; rotation $[\alpha]_D^{25} + 126^\circ$ (c., 0.8508, ethanol).

Analysis.—Calcd. for $C_{14}H_{23}NO_5S$: C, 52.95; H, 7.30; N, 4.41; S, 10.10; O, 25.20. Found: C, 52.77; H, 7.34; N, 4.40; S, 10.12; O, 25.11.

The aqueous mother liquors were concentrated in vacuo to give a solid which was recrystallized from acetone; it consisted of methyl N-acetyl-3,4-O-isopropylidene- α -thiolincosaminide of melting point 178–180° C. and rotation $[\alpha]_D^{25} + 189^\circ$ (c., 0.5137, water).

EXAMPLE 2

Conversion of the oxazoline derived from methyl N-acetyl-3,4-O-isopropylidene- α -thiolincosaminide to methyl N-acetyl-3,4-O-isopropylidene- α -thiolincosaminide

A solution was prepared of the oxazoline derived from methyl N-acetyl-3,4-O-isopropylidene- α -thiolincosaminide in 20 ml. of hot water and heated under reflux for 2 hours at which time thin-layer chromatography on silica gel revealed the conversion of the starting material to methyl N-acetyl-3,4-O-isopropylidene- α -thiolincosaminide.

The water was then removed in vacuo at 40° C., leaving a colorless crystalline solid which was recrystallized from a small volume of hot water to give colorless needles of methyl N-acetyl-3,4-O-isopropylidene- α -thiolincosaminide of melting point 178–180° C. and rotation $[\alpha]_D^{25} + 190^\circ$ (c., 1.223, water).

EXAMPLE 3

Methyl N-propionyl-3,4-O-isopropylidene- α -thiolincosaminide and the oxazoline derived therefrom

In the manner given in Example 1-B, methyl α -thiolincosaminide was treated with propionic anhydride in methanol solution to give methyl N-propionyl- α -thiolincosaminide.

The thus-obtained methyl N-propionyl- α -thiolincosaminide was finely powdered and suspended in dry acetone. Theroeto was added water-free ethylbenzenesulfonic acid and the mixture heated to 40° C. with rapid stirring for a period of 45 minutes. It was then allowed to stand at room temperature for 5 hours before neutralization with ammonia gas as in Example 1-C. The precipitated ammonium ethylbenzenesulfonate was removed by filtration and the filtrate was evaporated to dryness. The residue was treated with water and the crystalline material which did not dissolve was collected by filtration and recrystallized from acetone-Skellysolve B to give in crystalline form the oxazoline derived from methyl N-propionyl-3,4-O-isopropylidene- α -thiolincosaminide. The mother liquors were evaporated in vacuo to give methyl N-propionyl-3,4-O-isopropylidene- α -thiolincosaminide.

In the manner given in Example 2, the oxazoline derived from methyl N-propionyl-3,4-O-isopropylidene- α -thiolincosaminide can be converted to methyl N-propionyl-3,4-O-isopropylidene- α -thiolincosaminide by heating the product with water.

By treating methyl α -thiolincosaminide in the manner given in Example 1-B with other anhydrides for example butyric anhydride, valeric anhydride, hexanoic anhydride, benzoic anhydride, heptanoic anhydride, phenylacetic anhydride, octanoic anhydride, phenylpropionic anhydride, nonanoic anhydride, decanoic anhydride, undecanoic anhydride, lauric anhydride and the like, other methyl N-acyl- α -thiolincosaminides, such as methyl N-butryl-, N-valeryl-, N-hexanoyl-, N-benzoyl-, N-phenylacetyl-, N-heptanoyl-, N-octanoyl-, N-phenylpropionyl-, N-nonanoyl-, N-decanoyl-, N-undecanoyl- and N-lauroyl- α -thiolincosaminide.

In the manner given in Example 1-C, these methyl N-acyl- α -thiolincosaminides can be converted to the corresponding methyl N-acyl-3,4-O-isopropylidene- α -thiolincosaminides and the oxazolines derived therefrom, each pair of which can be separated into its components by their distinctive water-solubilities. Representative compounds thus obtained include methyl N-butryl-, N-valeryl-, N-hexanoyl-, N-heptanoyl-, N-benzoyl-, N-phenylacetyl-, N-phenylpropionyl-, N-octanoyl-, N-nonanoyl-, N-decanoyl-, N-undecanoyl- and N-lauroyl-3,4-O-isopropylidene- α -thiolincosaminide and the oxazolines derived therefrom.

In the manner given in Example 2, the above oxazolines can be converted to the corresponding methyl N-acyl-3,4-O-isopropylidene- α -thiolincosaminide, already mentioned above.

EXAMPLE 4

Methylation of methyl N-acetyl-3,4-O-isopropylidene- α -thiolincosaminide

Potassium metal (1.16 g.) was dissolved in 100 ml. of t-butyl alcohol (previously dried over sodium metal) under stirring and reflux. The solvent was removed as completely as possible by distillation and finally by distillation in a vacuum of 15 mm. Hg. To the dry, solid residue was added 100 ml. of dry benzene, which was removed by distillation to leave a fine powder. This was treated

again with benzene which was distilled off to insure complete removal of tert-butyl alcohol.

To the thus-obtained, powdery potassium tert-butoxide was added 200 ml. of dry benzene and the mixture was stirred magnetically at room temperature until an opalescent suspension resulted. To this was added 5 g. of methyl N-acetyl-3,4-O-isopropylidene- α -thiolincosaminide and the mixture was then stirred overnight at room temperature at the end of which time all of the solid had dissolved.

To this mixture was added 42.4 g. (18.6 ml.) of methyl iodide and the mixture was stirred at room temperature for 1½ hours; after 1 hour, the mixture gave a neutral reaction with moist pH paper. The reaction mixture was filtered to remove potassium iodide and the potassium iodide was washed with benzene; the benzene was added to the filtrate. The filtrate and washings were distilled in vacuo at 35° C. to give a colorless syrup which was subjected to counter current distribution in the system ethyl acetate:ethanol:water in the ratio 4:1:2. After 500 transfers the three components, as indicated by thin-layer chromatography, had been completely resolved. The major components were shown to be methyl N-acetyl-3,4-O-isopropylidene-7-O-methyl- α -thiolincosaminide (IV, $R_1=R_2=CH_3$), and methyl N-acetyl-3,4-O-isopropylidene-2-O-methyl- α -thiolincosaminide (V, $R_1=R_2=CH_3$). In addition a minor component was found, which was methyl N-acetyl-3,4-O-isopropylidene-2,7-di-O-methyl- α -thiolincosaminide (VI, $R_1=R_2=CH_3$).

Removal of solvents from combined tubes No. 250-310 ($K=1.30$) inclusive gave a glassy material which crystallized from ethyl acetate:Skellysolve B hexanes to yield methyl N-acetyl-3,4-O-isopropylidene-2-O-methyl- α -thiolincosaminide as short, colorless prisms of melting point 176-177° C. and rotation $[\alpha]_D^{25}+176^\circ$ (c., 0.6220, chloroform).

Analysis.—Calcd. for $C_{15}H_{27}NO_6S$: C, 51.57; H, 7.79; N, 4.01; S, 9.17; OMe, 8.88. Found: C, 51.82; H, 8.10; N, 4.08; S, 8.94; OMe, 8.49.

Removal of solvents from combined tubes No. 330-384 ($K=2.52$) inclusive by distillation gave a glassy product which crystallized slowly on standing. Recrystallization from ether gave clusters of minute, colorless needles of methyl N-acetyl-7-O-methyl-3,4-O-isopropylidene- α -thiolincosaminide (IV, $R_1=R_2=CH_3$).

Similarly, evaporation of the solvents from combined tubes No. 410-450 ($K=5.67$) gave a colorless glassy product. Recrystallization from ether gave colorless, chunky needles of methyl N-acetyl-2,7-di-O-methyl-3,4-O-isopropylidene- α -thiolincosaminide (VI, $R_1=R_2=CH_3$) of melting point 124.5-126° C. and rotation $[\alpha]_D^{25}+184^\circ$ (c., 0.8390, chloroform).

Analysis.—Calcd. for $C_{16}H_{29}NO_6S$: C, 52.88; H, 8.04; N, 3.85; S, 8.82; OCH₃, 17.08. Found: C, 53.02; H, 7.95; N, 4.05; S, 8.73; OCH₃, 15.92.

EXAMPLE 5

Ethylation of methyl N-acetyl-3,4-O-isopropylidene- α -thiolincosaminide

In the manner given in Example 4, a solution of methyl N-acetyl-3,4-O-isopropylidene- α -thiolincosaminide in benzene containing potassium tert-butoxide was treated with ethyl iodide to give methyl N-acetyl-3,4-O-isopropylidene-7-O-ethyl- α -thiolincosaminide, methyl N-acetyl-3,4-O-isopropylidene-2-O-ethyl- α -thiolincosaminide, and methyl N-acetyl-3,4-O-isopropylidene-2,7-di-O-ethyl- α -thiolincosaminide, which can be separated by counter current distribution as shown in Example 4.

EXAMPLE 6

Methylation of methyl N-propionyl-3,4-O-isopropylidene- α -thiolincosaminide

In the manner given in Example 4, methyl N-propionyl-3,4-O-isopropylidene- α -thiolincosaminide in ben-

zene solution was reacted with methyl iodide in the presence of potassium t-butoxide to give methyl N-propionyl-3,4-O-isopropylidene-7-O-methyl- α -thiolincosaminide, methyl N-propionyl-3,4-O-isopropylidene-2-O-methyl- α -thiolincosaminide, and methyl N-propionyl-3,4-O-isopropylidene-2,7-di-O-methyl- α -thiolincosaminide.

EXAMPLE 7

Butylation of methyl N-benzoyl-3,4-O-isopropylidene- α -thiolincosaminide

In the manner given in Example 4, methyl N-benzoyl-3,4-O-isopropylidene- α -thiolincosaminide, dissolved in benzene, is reacted with butyl iodide in the presence of potassium t-butoxide to give methyl N-benzoyl-3,4-O-isopropylidene-7-O-butyl- α -thiolincosaminide, methyl N-benzoyl-3,4-O-isopropylidene-2-O-butyl- α -thiolincosaminide and methyl N-benzoyl-3,4-O-isopropylidene-2,7-di-O-butyl- α -thiolincosaminide, which are separable by counter current distribution.

EXAMPLE 8

Hexylation of methyl N-hexanoyl-3,4-O-isopropylidene- α -thiolincosaminide

In the manner given in Example 4, methyl N-hexanoyl-3,4-O-isopropylidene- α -thiolincosaminide, dissolved in benzene, is reacted with hexyl iodide in the presence of potassium t-butoxide to give methyl N-hexanoyl-3,4-O-isopropylidene-7-O-hexyl- α -thiolincosaminide methyl N-hexanoyl-3,4-O-isopropylidene-2-O-hexyl- α -thiolincosaminide and methyl N-hexanoyl-3,4-O-isopropylidene-2,7-di-O-hexyl- α -thiolincosaminide, which are separable by counter current distribution.

EXAMPLE 9

Octylation of methyl N-valeryl-3,4-O-isopropylidene- α -thiolincosaminide

In the manner given in Example 4, methyl N-valeryl-3,4-O-isopropylidene- α -thiolincosaminide, dissolved in benzene, is reacted with octyl iodide in the presence of potassium tert-butoxide to give methyl N-valeryl-3,4-O-isopropylidene-7-O-octyl- α -thiolincosaminide, methyl N-valeryl-3,4-O-isopropylidene-2-O-octyl- α -thiolincosaminide and methyl N-valeryl-3,4-O-isopropylidene-2,7-di-O-octyl- α -thiolincosaminide, which are separable by counter current distribution.

EXAMPLE 10

Decylation of methyl N-acetyl-3,4-O-isopropylidene- α -thiolincosaminide

In the manner given in Example 4, methyl N-acetyl-3,4-O-isopropylidene- α -thiolincosaminide, dissolved in benzene, is reacted with decyl iodide in the presence of potassium tert-butoxide to give methyl N-acetyl-3,4-O-isopropylidene-7-O-decyl- α -thiolincosaminide, methyl N-acetyl-3,4-O-isopropylidene-2-O-decyl- α -thiolincosaminide and methyl N-acetyl-3,4-O-isopropylidene-2,7-di-O-decyl- α -thiolincosaminide, which are separable by counter current distribution.

EXAMPLE 11

Undecylation of methyl N-propionyl-3,4-O-isopropylidene- α -thiolincosaminide

In the manner given in Example 4, methyl N-propionyl-3,4-O-isopropylidene- α -thiolincosaminide, dissolved in benzene, is reacted with undecyl iodide in the presence of potassium tert-butoxide to give methyl N-propionyl-3,4-O-isopropylidene-7-O-undecyl- α -thiolincosaminide, methyl N-propionyl-3,4-O-isopropylidene-2-O-undecyl- α -thiolincosaminide and methyl N-propionyl-3,4-O-isopropylidene-2,7-di-O-undecyl- α -thiolincosaminide, which are separable by counter current distribution.

11

EXAMPLE 12

Dodecylation of methyl N-butryl-3,4-O-isopropylidene- α -thiolincosaminide

In the manner given in Example 4, methyl N-butyryl-3,4-O-isopropylidene- α -thiolincosaminide, dissolved in benzene, is reacted with dodecyl iodide in the presence of potassium tert-butoxide to give methyl N-butyryl-3,4-O-isopropylidene-7-O-dodecyl- α -thiolincosaminide, methyl N-butyryl-3,4-O-isopropylidene-2-O-dodecyl- α -thiolincosaminide and methyl N-butyryl-3,4-O-isopropylidene-2,7-di-O-dodecyl- α -thiolincosaminide, which are separable by counter current distribution.

EXAMPLE 13

Methylation of methyl N-lauroyl-3,4-O-isopropylidene- α -thiolincosaminide

In the manner given in Example 4, methyl N-lauroyl-3,4-O-isopropylidene- α -thiolincosaminide, dissolved in benzene, is reacted with methyl iodide in the presence of potassium tert-butoxide to give methyl N-lauroyl-3,4-O-isopropylidene-7-O-methyl- α -thiolincosaminide, methyl N-lauroyl-3,4-O-isopropylidene-2-O-methyl- α -thiolincosaminide and methyl N-lauroyl-3,4-O-isopropylidene-2,7-di-O-methyl- α -thiolincosaminide, which are separable by counter current distribution.

EXAMPLE 14

Ethylation of methyl N-undecanoyl-3,4-O-isopropylidene- α -thiolincosaminide

In the manner given in Example 4, methyl N-undecanoyl-3,4-O-isopropylidene- α -thiolincosaminide, dissolved in benzene, is reacted with ethyl iodide in the presence of potassium tert-butoxide to give methyl N-undecanoyl-3,4-O-isopropylidene-7-O-ethyl- α -thiolincosaminide, methyl N-undecanoyl-3,4-O-isopropylidene-2-O-ethyl- α -thiolincosaminide and methyl N-undecanoyl-3,4-O-isopropylidene-2,7-di-O-ethyl- α -thiolincosaminide, which are separable by counter current distribution.

EXAMPLE 15

Pentylation of methyl N-phenylpropionyl-3,4-O-isopropylidene- α -thiolincosaminide

In the manner given in Example 4, methyl N-phenylpropionyl-3,4-O-isopropylidene- α -thiolincosaminide, dissolved in benzene, is reacted with pentyl iodide in the presence of potassium tert-butoxide to give methyl N-phenylpropionyl-3,4-O-isopropylidene-7-O-pentyl- α -thiolincosaminide, methyl N-phenylpropionyl-3,4-O-isopropylidene-2-O-pentyl- α -thiolincosaminide and methyl N-phenylpropionyl-3,4-O-isopropylidene-2,7-di-O-pentyl- α -thiolincosaminide, which are separable by counter current distribution.

EXAMPLE 16

Nonylation of methyl N-phenylacetetyl-3,4-O-isopropylidene- α -thiolincosaminide

In the manner given in Example 4, methyl N-phenylacetetyl-3,4-O-isopropylidene- α -thiolincosaminide, dissolved in benzene, is reacted with nonyl iodide in the presence of potassium tert-butoxide to give methyl N-phenylacetetyl-3,4-O-isopropylidene-7-O-nonyl- α -thiolincosaminide, methyl N-phenylacetetyl-3,4-O-isopropylidene-2-O-nonyl- α -thiolincosaminide and methyl N-phenylacetetyl-3,4-O-isopropylidene-2,7-di-O-nonyl- α -thiolincosaminide, which are separable by counter current distribution.

EXAMPLE 17

N-acetyl-7-O-methyl-3,4-O-isopropylidene-1-deoxylincosamine (N-acetyl-7-O-methyl-3,4-O-isopropylidene-1,5-anhydrolincosaminol)

Twelve grams of methyl N-acetyl-7-O-methyl-3,4-O-isopropylidene- α -thiolincosaminide were dissolved in 500 ml. of ethanol and thereto was added 150 ml. of loosely

12

packed Raney nickel in ethanol. This mixture was heated under reflux for 10 hours. Thereafter the mixture was filtered, the catalyst was washed with 1 liter of boiling ethanol, and the washings were combined with the filtrate.

- 5 The filtrate and washings were then evaporated to dryness. The resulting product was distributed (500 transfers) in the system 1-butanol:water. The peak fractions were combined and crystallized from ethanol to give 7-O-methyl-N-acetyl-3,4-O-isopropylidene-1-deoxylincosamine of melting point 198-205°C. and rotation $[\alpha]_D^{25} +71^\circ$ (c., 1, 50% aqueous ethanol).

EXAMPLE 18

N-acetyl-2-O-methyl-3,4-O-isopropylidene-1-deoxylincosamine (VIII)

- 15 In the manner given in Example 17, methyl N-acetyl-2-O-methyl-3,4-O-isopropylidene- α -thiolincosaminide was desulfurized with Raney nickel in ethanol at reflux temperature to give 2-O-methyl-N-acetyl-3,4-O-isopropylidene-1-deoxylincosamine.

EXAMPLE 19

N-acetyl-2,7-di-O-methyl-3,4-O-isopropylidene-1-deoxylincosamine (IX)

- 20 25 In the manner given in Example 17, methyl N-acetyl-2,7-di-O-methyl-3,4-O-isopropylidene- α -thiolincosaminide was desulfurized with Raney nickel catalyst in ethanol solution at reflux to give N-acetyl-2,7-di-O-methyl-3,4-O-isopropylidene-1-deoxylincosamine of melting point 150-153°C. and rotation $[\alpha]_D^{25} +67^\circ$ (c., 0.8266, 50% aqueous ethanol).

EXAMPLE 20

N-propionyl-2-O-methyl-3,4-O-isopropylidene-1-deoxylincosamine

- 30 35 In the manner given in Example 17, methyl N-propionyl-2-O-methyl-3,4-O-isopropylidene- α -thiolincosaminide is desulfurized with Raney nickel in ethanol at reflux temperature to give N-propionyl-2-O-methyl-3,4-O-isopropylidene-1-deoxylincosamine.

EXAMPLE 21

N-propionyl-7-O-methyl-3,4-O-isopropylidene-1-deoxylincosamine

- 40 45 In the manner given in Example 17, methyl N-propionyl-7-O-methyl-3,4-O-isopropylidene- α -thiolincosaminide is desulfurized with Raney nickel in ethanol at reflux temperature to give N-propionyl-7-O-methyl-3,4-O-isopropylidene-1-deoxylincosamine.

EXAMPLE 22

N-propionyl-2,7-di-O-methyl-3,4-O-isopropylidene-1-deoxylincosamine

- 50 55 In the manner given in Example 17, methyl N-propionyl-2,7-di-O-methyl-3,4-O-isopropylidene- α -thiolincosaminide is desulfurized with Raney nickel in ethanol at reflux temperature to give N-propionyl-2,7-di-O-methyl-3,4-O-isopropylidene-1-deoxylincosamine.

EXAMPLE 23

N-butyryl-2-O-dodecyl-3,4-O-isopropylidene-1-deoxylincosamine

- 60 65 In the manner given in Example 17, methyl N-butyryl-2-O-dodecyl-3,4-O-isopropylidene- α -thiolincosaminide is desulfurized with Raney nickel in ethanol at reflux temperature to give N-butyryl-2-O-dodecyl-3,4-O-isopropylidene-1-deoxylincosamine.

EXAMPLE 24

N-benzoyl-2-O-butyl-3,4-O-isopropylidene-1-deoxylincosamine

- 70 75 In the manner given in Example 17, methyl N-benzoyl-2-O-butyl-3,4-O-isopropylidene- α -thiolincosaminide

13

is desulfurized with Raney nickel in ethanol at reflux temperature to give N-benzoyl-2-O-butyl-3,4-O-isopropylidene-1-deoxylincosamine.

EXAMPLE 25

N-propionyl-2-O-undecyl-3,4-O-isopropylidene-1-deoxylincosamine

In the manner given in Example 17, methyl N-propionyl-2-O-undecyl-3,4-O-isopropylidene- α -thiolincosaminide is desulfurized with Raney nickel in ethanol at reflux temperature to give N-propionyl-2-O-undecyl-3,4-O-isopropylidene-1-deoxylincosamine.

EXAMPLE 26

N-lauroyl-2-O-methyl-3,4-O-isopropylidene-1-deoxylincosamine

In the manner given in Example 17, methyl N-lauroyl-2-O-methyl-3,4-O-isopropylidene- α -thiolincosaminide is desulfurized with Raney nickel in ethanol at reflux temperature to give N-lauroyl-2-O-methyl-3,4-O-isopropylidene-1-deoxylincosamine.

EXAMPLE 27

N-undecanoyl-2-O-ethyl-3,4-O-isopropylidene-1-deoxylincosamine

In the manner given in Example 17, methyl N-undecanoyl-2-O-ethyl-3,4-O-isopropylidene- α -thiolincosaminide is desulfurized with Raney nickel in ethanol at reflux temperature to give N-undecanoyl-2-O-ethyl-3,4-O-isopropylidene-1-deoxylincosamine.

EXAMPLE 28

N-phenylpropionyl-2,7-di-O-pentyl-3,4-O-isopropylidene-1-deoxylincosamine

In the manner given in Example 17, methyl N-phenylpropionyl-2,7-di-O-pentyl-3,4-O-isopropylidene- α -thiolincosaminide is desulfurized with Raney nickel in ethanol at reflux temperature to give N-phenylpropionyl-2,7-di-O-pentyl-3,4-O-isopropylidene-1-deoxylincosamine.

EXAMPLE 29

N-phenylacetyl-2,7-di-O-nonyl-3,4-O-isopropylidene-1-deoxylincosamine

In the manner given in Example 17, methyl N-phenylacetyl-2,7-di-O-nonyl-3,4-O-isopropylidene- α -thiolincosaminide is desulfurized with Raney nickel in ethanol at reflux temperature to give N-phenylacetyl-2,7-di-O-nonyl-3,4-O-isopropylidene-1-deoxylincosamine.

EXAMPLE 30

N-valeryl-7-O-octyl-3,4-O-isopropylidene-1-deoxylincosamine

In the manner given in Example 17, methyl N-valeryl-7-O-octyl-3,4-O-isopropylidene- α -thiolincosaminide is desulfurized with Raney nickel in ethanol at reflux temperature to give N-valeryl-7-O-octyl-3,4-O-isopropylidene-1-deoxylincosamine.

Other compounds prepared in the manner given in Example 17 include:

N-heptanoyl-2-O-pentyl-3,4-O-isopropylidene-1-deoxylincosamine,
N-octanoyl-2-O-hexyl-3,4-O-isopropylidene-1-deoxylincosamine,
N-valeryl-2-O-heptyl-3,4-O-isopropylidene-1-deoxylincosamine,
N-isobutyryl-2-O-octyl-3,4-O-isopropylidene-1-deoxylincosamine,
N-acetyl-2-O-nonyl-3,4-O-isopropylidene-1-deoxylincosamine,

14

N-propionyl-2-O-decyl-3,4-O-isopropylidene-1-deoxylincosamine,
N-propionyl-2,7-di-O-butyl-3,4-O-isopropylidene-1-deoxylincosamine,
N-phenylacetyl-2,7-di-O-hexyl-3,4-O-isopropylidene-1-deoxylincosamine,
N-valeryl-2,7-di-O-octyl-3,4-O-isopropylidene-1-deoxylincosamine,
N-propionyl-2,7-di-O-dodecyl-3,4-O-isopropylidene-1-deoxylincosamine,
N-isovaleryl-2,7-di-O-decyl-3,4-O-isopropylidene-1-deoxylincosamine,
N-propionyl-2,7-di-O-undecyl-3,4-O-isopropylidene-1-deoxylincosamine, and the like.

15

EXAMPLE 31

Methyl 2-O-methyl- α -thiolincosaminide

A solution of 2 g. of methyl N-acetyl-2-O-methyl-3,4-O-isopropylidene- α -thiolincosaminide in 50 ml. of 0.25 N hydrochloric acid was magnetically stirred at room temperature (about 25° C.). The solid starting material dissolved within minutes. After 1 1/4 hours, thin-layer chromatography showed the complete absence of starting material.

20 The strongly acidic solution was stirred with an anion exchange resin, Amberlite IRA-400 (OH⁻ form) until the colorless supernatant solution gave a neutral reaction with pH paper. Filtration, washing of the resin with water, and removal of the water from the combined filtrate and washes in vacuo gave 1.68 g. (95%) of a colorless crystalline residue which was crystallized from methanol-ether to give long colorless felted needles of methyl N-acetyl-2-O-methyl- α -thiolincosaminide of melting point 237-238° C.

25 *Analysis.*—Calcd. for C₁₂H₂₃NO₆S: C, 46.56; H, 7.49; N, 4.53; S, 10.36. Found: C, 46.72; H, 7.44; N, 4.37; S, 10.34.

30 The thus-obtained methyl N-acetyl-2-O-methyl- α -thiolincosaminide was heated with 6 ml. of hydrazine hydrate under reflux for a period of 22 hours. The excess hydrazine hydrate was removed by distillation in vacuo and the residue was three times recrystallized from ethanol-water to give methyl 2-O-methyl- α -thiolincosaminide.

35

EXAMPLE 32

Methyl 7-O-methyl- α -thiolincosaminide

40 In the manner given in Example 31, methyl N-acetyl-7-O-methyl-3,4-O-isopropylidene- α -thiolincosaminide was hydrolyzed and then hydrazinolized to give methyl 7-O-methyl- α -thiolincosaminide.

45

EXAMPLE 33

Methyl 2,7-di-O-methyl- α -thiolincosaminide

45 In the manner given in Example 31, methyl N-acetyl-2,7-di-O-methyl-3,4-O-isopropylidene- α -thiolincosaminide was hydrolyzed and then hydrazinolized to give methyl 2,7-O-methyl- α -thiolincosaminide.

50

EXAMPLE 34

Methyl 7-O-ethyl- α -thiolincosaminide

55 In the manner given in Example 31, methyl N-acetyl-7-O-ethyl-3,4-O-isopropylidene- α -thiolincosaminide was hydrolyzed and then hydrazinolized to give methyl 7-O-ethyl- α -thiolincosaminide.

60

EXAMPLE 35

Methyl 2-O-butyl- α -thiolincosaminide

65 In the manner given in Example 31, methyl N-acetyl-2-O-butyl-3,4-O-isopropylidene- α -thiolincosaminide was hydrolyzed and then hydrazinolized to give methyl 2-O-butyl- α -thiolincosaminide.

70

70

15

EXAMPLE 36

Methyl 2,7-di-O-hexyl- α -thiolincosaminide

In the manner given in Example 31, methyl N-acetyl-2,7-di-O-hexyl-3,4-O-isopropylidene- α -thiolincosaminide was hydrolyzed and then hydrazinolized to give methyl 2,7-di-O-hexyl- α -thiolincosaminide.

EXAMPLE 37

Methyl 2-O-dodecyl- α -thiolincosaminide

In the manner given in Example 31, methyl N-acetyl-2-O-dodecyl-3,4-O-isopropylidene- α -thiolincosaminide was hydrolyzed and then hydrazinolized to give methyl 2-O-dodecyl- α -thiolincosaminide.

EXAMPLE 38

7-O-methyl-1-deoxylincosamine

In the manner given in Example 31, N-acetyl-7-O-methyl-3,4-O-isopropylidene-1-deoxylincosamine was hydrolyzed and subsequently hydrazinolized to give 7-O-methyl-1-deoxylincosamine.

EXAMPLE 39

2-O-methyl-1-deoxylincosamine

In the manner given in Example 31, N-acetyl-2-O-methyl-3,4-O-isopropylidene-1-deoxylincosamine was hydrolyzed and subsequently hydrazinolized to give 2-O-methyl-1-deoxylincosamine.

EXAMPLE 40

2,7-di-O-methyl-1-deoxylincosamine

In the manner given in Example 31, N-acetyl-2,7-di-O-methyl-3,4-O-isopropylidene-1-deoxylincosamine was hydrolyzed and subsequently hydrazinolized to give 2,7-di-O-methyl-1-deoxylincosamine.

EXAMPLE 41

7-O-ethyl-1-deoxylincosamine

In the manner given in Example 31, N-acetyl-7-O-ethyl-3,4-O-isopropylidene-1-deoxylincosamine was hydrolyzed and subsequently hydrazinolized to give 7-O-ethyl-1-deoxylincosamine.

EXAMPLE 42

7-O-hexyl-1-deoxylincosamine

In the manner given in Example 31, N-acetyl-7-O-hexyl-3,4-O-isopropylidene-1-deoxylincosamine was hydrolyzed and subsequently hydrazinolized to give 7-O-hexyl-1-deoxylincosamine.

EXAMPLE 43

7-O-decyl-1-deoxylincosamine

In the manner given in Example 31, N-acetyl-7-O-decyl-3,4-O-isopropylidene-1-deoxylincosamine was hydrolyzed and subsequently hydrazinolized to give 7-O-decyl-1-deoxylincosamine.

16

drolyzed and subsequently hydrazinolized to give 2-O-dodecyl-1-deoxylincosamine.

Example 45

2,7-O-octyl-1-deoxylincosamine

In the manner given in Example 31, N-acetyl-2,7-O-octyl-3,4-O-isopropylidene-1-deoxylincosamine was hydrolyzed and subsequently hydrazinolized to give 2,7-O-octyl-1-deoxylincosamine.

EXAMPLE 46

2-O-ethyl-1-deoxylincosamine from methyl 2-O-ethyl- α -thiolincosaminide

Two grams of methyl 2-O-ethyl- α -thiolincosaminide were dissolved in 80 ml. of ethanol and thereto was added 25 ml. of loosely-packed Raney nickel in ethanol. This mixture was heated under reflux for 10 hours, cooled and filtered. The catalyst was washed with 150 ml. of boiling ethanol, and the washings and filtrate were combined and evaporated to dryness. The resulting residue was distributed in the system 1-butanol:water. The peak fractions containing 2-O-ethyl-1-deoxylincosamine as determined by thin-layer chromatography were combined, evaporated and crystallized from ethanol to give 2-O-ethyl-1-deoxylincosamine.

In the manner given in Example 46, other 2-O-alkyl-7-O-alkyl- and 2,7-di-O-alkyl-1-deoxylincosamines can be obtained from the corresponding methyl 2-O-alkyl-, 7-O-alkyl- and 2,7-di-O-alkyl- α -thiolincosaminides by desulfurization with Raney nickel.

We claim:

1. An oxazoline having the structural formula

50 wherein R₁ is selected from the group consisting of alkyl and aralkyl containing from 1 to 11 carbon atoms, inclusive.

2. The oxazoline derived from methyl N-acetyl-3,4-O-isopropylidene- α -thiolincosaminide.

55 3. A methyl O-alkyl-substituted- α -thiolincosaminide selected from the group consisting of compounds having the structural formulae:

wherein R₂ is an alkyl group having from 1 to 12 carbon atoms, inclusive.

4. Methyl 2-O-methyl- α -thiolincosaminide.

5. Methyl 7-O-methyl- α -thiolincosaminide.

6. Methyl 2,7-di-O-methyl- α -thiolincosaminide.

EXAMPLE 44

2-O-dodecyl-1-deoxylincosamine

In the manner given in Example 31, N-acetyl-2-O-dodecyl-3,4-O-isopropylidene-1-deoxylincosamine was hy-

7. An O-alkyl-substituted-1-deoxylincosamine selected from the group consisting of compounds having the structural formulae:

wherein R₂ is an alkyl group having from 1 to 12 carbon atoms, inclusive.

8. 2-O-methyl-1-deoxylincosamine.

9. 7-O-methyl-1-deoxylincosamine.

10. 2,7-di-O-methyl-1-deoxylincosamine.

11. A process for the preparation of an N-acyl-3,4-O-isopropylidene-1-deoxylincosamine selected from the group consisting of compounds having the structural formulae:

wherein R₁ is selected from the group consisting of alkyl and aralkyl containing from 1 to 11 carbon atoms, inclusive, and wherein R₂ is an alkyl group having from 1 to 12 carbon atoms, inclusive, which comprises: treating a methyl N-acyl- α -thiolincosaminide of the formula:

wherein R₁ is defined as above, with acetone and an acid catalyst to obtain a mixture of a methyl N-acyl-3,4-O-isopropylidene- α -thiolincosaminide and the oxazoline thereof; separating the methyl N-acyl-3,4-O-isopropylidene- α -thiolincosaminide from the oxazoline thereof and hydrolyzing the oxazoline to the methyl N-acyl-3,4-O-isopropylidene- α -thiolincosaminide; alkylating this compound with an alkyl halide selected from the group consisting of alkyl chlorides, alkyl bromides and alkyl iodides in which the alkyl group has from 1 to 12 carbon atoms, inclusive, in the presence of a base; separating the thus-obtained methyl N-acyl-3,4-O-isopropylidene-2-O-alkyl- α -thiolincosaminide, methyl N-acyl-3,4-O-isopropylidene-7-O-alkyl- α -thiolincosaminide and methyl N-acyl-3,4-O-iso-

propylidene-2,7-di-O-alkyl- α -thiolincosaminide from each other; and desulfurizing separately each of these compounds with a nickel catalyst in a lower alkanol to obtain

15 separately the corresponding N-acyl-2-O-alkyl-3,4-isopropylidene-1-deoxylincosamine, N-acyl-7-O-alkyl-3,4-O-isopropylidene-1-deoxylincosamine and N-alkyl-2,7-di-O-alkyl-3,4-O-isopropylidene-1-deoxylincosamine.

12. The process of claim 11, wherein the starting material is methyl N-acetyl- α -thiolincosaminide, the alkyl halide is methyl iodide, and the final products are 2-O-methyl - N - acetyl - 3,4 - O - isopropylidene - 1 - deoxylincosamine, 7-O-methyl-N-acetyl - 3,4-O-isopropylidene-

1-deoxylincosamine and 2,7-di-O-methyl-N-acetyl-3,4-O-isopropylidene-1-deoxylincosamine.

13. A process for the preparation of an O-alkyl-substituted- α -thiolincosaminide selected from the group consisting of compounds having the structural formulae:

wherein R₂ is an alkyl group having from 1 to 12 carbon atoms, inclusive, which comprises: treating a methyl N-acyl- α -thiolincosaminide of the formula:

55

60

65 wherein R₁ is selected from the group consisting of alkyl and aralkyl containing from 1 to 11 carbon atoms, inclusive, with acetone and an acid catalyst to obtain a methyl N-acyl-3,4-O-isopropylidene- α -thiolincosaminide and the oxazoline thereof; separating the methyl N-acyl-3,4-O-isopropylidene- α -thiolincosaminide from the oxazoline thereof and hydrolyzing the oxazoline to the methyl N-acyl-3,4-O-isopropylidene- α -thiolincosaminide; alkylating this compound with an alkyl halide selected from the group consisting of alkyl chlorides, alkyl bromides and alkyl iodides in which the alkyl group has from 1 to 12 carbon atoms, inclusive, in the presence of a base; separating the thus-obtained methyl N-acyl-3,4-O-isopropylidene-2-O-alkyl- α -thiolincosaminide, methyl N-acyl-3,4-O-isopropylidene-7-O-alkyl- α -thiolincosaminide and methyl N-acyl-3,4-O-iso-

75 alkyl iodides in which the alkyl group has from 1 to 12

carbon atoms, inclusive, in the presence of a base; separating the thus-obtained methyl N-acyl-3,4-O-isopropylidene-2-O-alkyl- α -thiolincosaminide, methyl N-acyl-3,4-O-isopropylidene-7-O-alkyl- α -thiolincosaminide and methyl N-acyl-3,4-O-isopropylidene-2,7-di-O-alkyl- α -thiolincosaminide from each other; separately hydrolyzing the thus-obtained compounds with a mineral acid and treating the obtained products with hydrazine hydrate to obtain the methyl 2-O-alkyl- α -thiolincosaminide, methyl 7-O-alkyl- α -thiolincosaminide and methyl 2,7-di-O-alkyl- α -thiolincosaminide.

14. A process for the preparation of an O-alkyl-1-deoxylincosamine selected from the group consisting of compounds having the structural formulae:

wherein R₂ is an alkyl group having from 1 to 12 carbon atoms, inclusive, which comprises: treating a methyl N-acyl- α -thiolincosaminide of the formula:

wherein R₁ is selected from the group consisting of alkyl and aralkyl containing from 1 to 11 carbon atoms, inclusive, with acetone and an acid catalyst to obtain a methyl N-acyl-3,4-O-isopropylidene- α -thiolincosaminide

40

and the oxazoline thereof; separating said methyl N-acyl-3,4-O-isopropylidene- α -thiolincosaminide from the oxazoline thereof and hydrolyzing the oxazoline to the methyl N-acyl-3,4-O-isopropylidene- α -thiolincosaminide; 5 alkylating this compound with an alkyl halide selected from the group consisting of alkyl chlorides, alkyl bromides and alkyl iodides in which the alkyl group has from 1 to 12 carbon atoms, inclusive, in the presence of a base; separating the thus-obtained methyl N-acyl-3,4-O-isopropylidene-2-O-alkyl- α -thiolincosaminide, methyl N-acyl-3,4-O-isopropylidene-7-O-alkyl- α -thiolincosaminide and methyl N-acyl-3,4-O-isopropylidene-2,7-di-O-alkyl- α -thiolincosaminide from each other; desulfurizing separately each of these compounds with a nickel

catalyst in a lower alkanol to obtain separately the corresponding N-acyl-2-O-alkyl-3,4-O-isopropylidene-1-deoxylincosamine, N-acyl-7-O-alkyl-3,4-O-isopropylidene-1-deoxylincosamine and N-acyl-2,7-di-O-alkyl-3,4-O-isopropylidene-1-deoxylincosamine; separately hydrolyzing the thus-obtained compound with a mineral acid and treating the obtained products with hydrazine hydrate to obtain 2-O-alkyl-1-deoxylincosamine, 7-O-alkyl-1-deoxylincosamine and 2,7-di-O-alkyl-1-deoxylincosamine.
